UNITED STATES PATENT OFFICE.

WALTER MCKENZIE, OF DETROIT, MICHIGAN.

TOOL-HANDLE.

1,341,378.

Specification of Letters Patent. Patented May 25, 1920.

Application filed March 1, 1919. Serial No. 280,070.

To all whom it may concern:

Be it known that I, WALTER MCKENZIE, a citizen of the United States, residing at Detroit, in the county of Wayne and State 5 of Michigan, have invented certain new and useful Improvements in Tool-Handles; and I do hereby declare the following to be a full, clear, and exact description of the invention, such as will enable others skilled 10 in the art to which it appertains to make and use the same.

This invention relates to tool handles, and more particularly to a handle for hammers and similar tools.

15 The primary object of the invention is to provide a handle constructed of strands of wire which are so wound as to effectively prevent separation or loosening of the strands, the end portions of the strands being 20 so related and formed as to effectually lock the wire strands together, the straightened end portions also providing means whereby the handle may be readily secured in the eye 25 of a hammer head and a gripping member may be tightly secured to this handle.

A further object is to provide a handle of the character stated which is light and durable while possessing sufficient resiliency to absorb all shocks and jars incident to the 30 use of the hammer.

Another object is to provide a handle of comparatively simple construction which may be readily produced at small cost by a simple wrapping or winding operation of 35 the wire strands.

Further objects will appear from the detailed description.

In the drawings:

Figure 1 is a side view, partly in section, 40 of a hammer with a handle constructed in accordance with my invention applied.

Fig. 2 is a central longitudinal section through the handle the gripping member being omitted.

45 Fig. 3 is a transverse section taken through the gripping portion of the handle.

Fig. 4 is a transverse section through the smaller end portion of the handle.

Fig. 5 is a fragmentary plan view of a 50 modified form of my invention.

In constructing the handle I employ a plurality of strands of wire which are disposed in two series, an inner series and an outer series. The strands 1 of the inner 55 series are wound in spiral form in one direction so as to provide an inner structure

of the shape of a hammer handle, the winding starting preferably at a central point to provide a reduced neck portion 2, and the convolutions of the winding increasing uniformly in diameter toward each end of the handle. The end portions of the strands 1, after the body portion of the handle has attained the desired length, are then bent or offset so as to extend longitudinally of the 60 handle, as at 1^a. This inner structure is enclosed by an outer structure or casing which is formed of wire strands 3 fitting snugly about the strands 1 and coiled in the opposite direction thereto. These outer strands 65 also have their end portions straight and offset so as to extend in parallel spaced relation to the portions 1^a, as at 3^a. As will be noted more clearly from Fig. 3, the end portions 1^a of strands 1 are so disposed as to 70 be positioned in the plane of the end portions 3^a of strands 3, this interposing and offsetting of the portions 1^a and 3^a of the wire strands of the inner and outer structures serving to effectually lock the strands 75 of the handle together so as to eliminate all possibility of the same becoming in any way detached. As a further security against detachment of the wire strands, or relative movement between these members, these 80 strands are preferably longitudinally corrugated as in Figs. 1 and 2. When the strands 3 of the outer structure are wrapped tightly about the strands 1 of the inner structure, these corrugations interlock, the 85 handle thus produced being very strong and having the requisite rigidity while, due to the inherent resiliency of the wire strands, being well adapted to absorb shock and jars 90 incident to use of the hammer.

95 After the handle body has been thus formed, a suitable core is placed in the larger end thereof, and a reinforcing and gripping member 4 is formed thereon by pouring molten metal, preferably aluminum, upon the straight portions 1^a and 3^a of the wire strands. As stated, these portions are spaced a short distance apart so that this metal flows between these strands forming an inner tubular reinforcing member 5 100 which is integrally connected to an outer reinforcing and gripping member 6, the interlocking straight portions of the strands being thus tightly secured together against relative movement, this securing of the 105 strands serving to effectually prevent all possibility of disengagement or looseness 110

thereof. The straight portions 1^a and 3^a of the wire strands, at the smaller end of the handle are, like the straight portions of the strands at the gripping end of the handle, disposed in substantial elliptical shape so as to be readily insertible through the eye of a hammer head 7, this eye tapering rearwardly in the well known manner. After the smaller end of the handle has been inserted into the eye, the head is secured thereon by pouring molten metal, preferably Babbitt metal, into this eye so as to flow between and about the wire strands. As these wire strands are corrugated, the metal plug thus produced serves to effectually secure the hammer head upon the handle and eliminates all possibility of accidental detachment thereof. The handle may be readily formed by winding or twisting from wire strands of suitable gage so as to correspond in size and shape to the well known wooden handle and may be produced at very small cost.

As will be seen upon reference to Fig. 5 of the drawings, this handle may also be readily formed by braiding the strands of wire together instead of coiling them spirally as in Figs. 1 to 4, inclusive. The handle formed in this manner may be readily produced and possesses the desired rigidity and strength while also having an appreciable amount of resiliency.

It will be evident that there may be slight changes made in the construction and arrangement of the details of my invention without departing from the field and scope of the same, and I intend to include all such variations, as fall within the scope of the appended claims, in this application in which the preferred forms only of my invention are disclosed.

What I claim is:

1. In a tool handle, an inner series of wire strands twisted spirally and having their end portions extended longitudinally of the handle, and an outer series of wire strands twisted spirally about said inner series and having their end portions extended longitudinally of the handle, the end portions of said inner series of wires being upwardly off-set and interposed with the end portions of the outer series so as to prevent relative movement between the strands of said inner and outer series.
2. In a tool handle, an inner series of wire strands twisted spirally so as to produce a handle form, and an outer series of wire strands twisted spirally about said inner series, the strands of the inner series and

the strands of the outer series being longitudinally corrugated so as to prevent relative movement between the strands of the two series.

3. In a tool handle, an inner series of wire strands twisted spirally into handle form, and an outer series of wire strands twisted spirally in the opposite direction to the strands of the inner series and fitting tightly about the same, the end portions of the wires of the two series being straight and extending longitudinally of the handle, said straight end portions of the inner series of wires being interposed with the straight end portions of the outer series of wires for securing the wires of the two series against relative movement.

4. In a tool handle, an inner series of wire strands twisted in spiral shape and having their end portions straight and extending longitudinally of the handle, an outer series of wire strands twisted spirally about said inner series and having their end portions straight and extending longitudinally of the handle, the straight end portions of the wires of the inner series being disposed between and in spaced relation to the straight end portions of the wires of the outer series, the straight end portions of the wires at one end of the handle being disposed to form an element adapted to be inserted through the eye of a hammer head, and a reinforcing and gripping member cast about the straight end portions of the wires at the other end of the handle so as to provide integrally connected inner and outer reinforcing elements, the straight portions of the wires being embedded in said member and secured against relative movement thereby.

5. The combination with a tool head provided with an eye, of a handle formed from a plurality of strands of wire coiled to provide a body portion, the end portions of the strands at one end of said body being disposed longitudinally and spaced apart to provide a hollow element for insertion into the eye of the tool head, and a securing plug formed of molten metal poured into the eye of the head and completely surrounding the strands of the end portions of said body so as to prevent withdrawal thereof from said tool head.

In testimony whereof I affix my signature in presence of two witnesses.

WALTER MCKENZIE.
